UNITED STATES PATENT OFFICE.

HERMAN A. OLSSON, OF QUINCY, MASSACHUSETTS.

AUTOMATIC ELECTRIC FIRE-ALARM.

SPECIFICATION forming part of Letters Patent No. 605,795, dated June 14, 1898.

Application filed June 17, 1897. Serial No. 641,135. (No model.)

To all whom it may concern:

Be it known that I, HERMAN A. OLSSON, a citizen of Sweden, and a resident of Quincy, in the county of Norfolk and State of Massachusetts, have invented new and useful Improvements in Automatic Electric Fire-Alarms, of which the following, taken in connection with the accompanying drawings, is a specification.

10 This invention relates to improvements in automatic electric fire-alarms for the purpose of notifying the occupants of a house of a fire occurring in any one of the rooms in the building, and it is so constructed as to automatically sound an alarm to indicate in which of the rooms of the house the fire is started, thus enabling the occupants to concentrate their efforts on such room in extinguishing the fire.

15 If so desired, the automatic alarm may be connected to neighboring houses or buildings, so as to notify the occupants of such adjacent buildings in case the persons in the building on fire should be absent, as will hereinafter be more fully shown and described, reference being had to the accompanying drawings, wherein—

Figure 1 represents a diagram showing the circuit-interrupters, alarms, and fusible cords arranged in a series of rooms or apartments 20 in a house or building. Fig. 2 represents a detail side elevation of one of the circuit-interrupters. Fig. 3 represents a top plan view of Fig. 2. Fig. 4 represents a cross-section on the line 4-4, shown in Fig. 3; and Fig. 35 represents a detail interior view of one of the alarms.

Similar letters refer to similar parts wherever they occur on the different parts of the drawings.

40 In the drawings, Fig. 1, A' A'' A³ A⁴ represent a series of rooms in a house or building. In each such room is located an electric-circuit interrupter B and an alarm C, electrically connected to other similar instruments 45 in the other rooms, as well as to a battery or electric-current generator D, as shown.

Each circuit-interrupter is provided with a spring-actuated shaft or barrel b, to which is attached a spring b', having its other end attached to the case B.

In practice a gear b'' is attached to the shaft b, with its teeth intermeshing in a pinion b³,

secured to a rotary shaft b⁴, provided with a retarding device or escapement b⁵, as shown.

To the shaft b is attached a notched disk b⁶ 55 for a purpose as will hereinafter be described, and to said shaft is also secured a pulley b⁷, to which one end of a fusible cord E is attached. The other end of said cord is attached to any stationary object within the room after being guided in various directions within said room, as indicated in Fig. 1.

In connection with each current-interrupter I use a spring-pressed lever F, having a tooth or projection f, normally held in yielding contact with the disk b⁶, as shown. Each lever F has in its free end an electrode or contact-point f', which is normally held out of contact with an insulated electrode G, preferably attached to the case B, as shown.

70 I wish to state that I do not desire to confine myself to any particular clock mechanism for rotating the toothed or notched disk b⁶, as this may be done in any well-known manner and by means of any suitable clock mechanism, and I have simply illustrated in the drawings a suitable mechanism for this purpose; but equivalent means may be used without departing from the essence of my invention.

80 In each room is located, as before stated, an alarm C, which may be of any well-known form. I have shown in the drawings, Fig. 5, such alarm as consisting of an electromagnet C' and a pivoted armature C'', provided with a hammer C³, adapted to strike a bell C⁴ when the circuit is closed through the electromagnet. Normally the hammer C³ is held from contact with the bell by means of a suitable spring C⁵, as is common in devices of this kind.

85 The notched wheel or disk b⁶ in each room is made different from the others in the arrangement of its teeth or notches. Thus, for instance, said disk in the room A' is provided with notches so as to intermittently close and open the circuit to sound an alarm "3 2" when its clock mechanism is released. Another may be arranged to sound "2 3," "1 2," "1 4," and so on through the different rooms.

90 From the battery or current-generator D leads a wire H to the insulated electrodes G on the interrupters B B B B in the series, as shown in Fig. 1. From the other pole of the

battery or current-generator D leads a wire I to and through the spools of the electromagnets in the series of alarms C C C C, as shown in Fig. 1.

- 5 The movable electrodes $f' f' f' f'$ are electrically connected by means of a wire K, said wire being also electrically connected to and through the electromagnets on the alarm, as shown in Fig. 1.
- 10 The fusible cord E is preferably made of hemp, cotton, or other suitable combustible material; but, if so desired, it may be made of metal provided at intervals with fusible metal couplings or connections, as is common
- 15 in automatic electric fire-alarms.

From the above it will be seen that if a fire should occur in one of the rooms—for instance, room A'—the cord E when burned off will release the spring-actuated notched disk b^6 ,
 20 which will be caused to rotate in the direction shown by arrow in Fig. 2, causing the circuit to be alternately closed and opened through all the alarms in the circuit, by which the alarm "3 2" is sounded not alone in the
 25 room where the fire occurs, but as well in all the other electrically-connected rooms, thus notifying the occupants of room A' that there is a fire in said room and also automatically notifying the occupants of rooms A'' A³ A⁴,
 30 &c., that there is a fire in room A'. Likewise, if a fire should occur in room A'', as soon as its cord E is burned off or released by the heat
 35 the alarm "2 3" will be automatically sounded in said room and all the other electrically-connected rooms, by which notice is given by the alarm to the occupants of all the rooms that there is a fire in room A'', and so on. Thus the occupants of a house, hotel, or other build-

ing are automatically notified in what particular room or portion of the building the fire is, 40 and they may therefore be enabled to act accordingly either in aiding to put out the fire or escape from the building, as may be most desirable. By this arrangement great assistance is rendered the firemen in locating a fire 45 in a building, as by the number of the alarm sounded they will know exactly in what room or portion of the building the fire is raging.

Having thus fully described the nature, construction, and operation of my invention, I 50 wish to secure by Letters Patent and claim—

In an automatic-electric-fire-alarm system in combination, an electric-current generator, a series of current-interrupters and alarms electrically connected to the current-generator 55 one in each room of the building, each such current-interrupter having a spring-actuated circuit breaking and closing disk differing from the others in the series and a fusible cord or wire for normally holding such 60 disk stationary and to cause it to be released when said cord or wire is ignited or fused by which the circuit is alternately closed and opened to cause an alarm corresponding to the number of the room in which the fire occurs to be automatically sounded in all the other rooms in the circuit substantially as 65 and for the purpose set forth.

In testimony whereof I have signed my name to this specification, in the presence of 70 two subscribing witnesses, on this 12th day of June, A. D. 1897.

HERMAN A. OLSSON.
